Attorney

UNITED STATES PATENT OFFICE

JOHN E. OLSON, OF BLOOMFIELD, NEBRASKA

SPARK-PLUG WRENCH

Application filed August 12, 1926. Serial No. 128,875.

My invention relates to wrenches of that particular type used for removing spark plugs from engine blocks as well as for separating the parts of spark plugs in order to thoroughly clean the same or replace parts thereof.

5 My invention contemplates providing a wrench with a pair of heads having handles, one of the heads being rotatably mounted in the other and both having sockets through the same in alinement with each other but of different sizes for receiving the wrench engaging portions of a spark plug, the handles providing for turning the heads of the wrench with relation to each other in order 10 to hold one part while turning the other thereon, as for instance the shell of a spark plug while the gland is being turned.

A further object of the invention is the provision of a novel manner of rotatably 20 mounting one head on the other, the construction of which will permit the heads to be readily separated when desired and securely connected for use in association with each other.

25 A still further object of the invention is to provide cooperating jaws on the outer ends of the handles which are adapted to be brought towards each other and grip the threaded nut that connects the electric conductor wire to the central electrode of the plug for turning the same.

It is also an object of the invention to provide a wrench of the above indicated character, which is simple and substantial in construction, can be manufactured economically, 35 and will be thoroughly efficient and practical in use.

With the foregoing and other objects in view, which will be apparent as the description 40 proceeds, the invention resides in the construction and arrangement of parts, as hereinafter described and claimed, it being understood that obvious changes can be made within the scope of what is claimed, without departing from the spirit of the invention.

The invention is illustrated in the accompanying drawing, wherein:

Figure 1 is a perspective view of my improved wrench,

50 Figure 2 is a section through the heads of

the wrench, showing the handles in elevation,

Figure 3 is a plan of the lower head and the handle attached thereto, showing the upper head and its handle in dotted lines,

55 Figure 4 is a fragmentary section similar to Figure 2 with the upper head and means for retaining the same in position removed.

Figure 5 is a perspective view of the retainer for the upper head, and

60 Figure 6 is a fragmentary bottom plan of the handles showing the gripping jaws thereon.

Referring to the drawings the numeral 10 designates a head of cylindrical formation

65 from which projects a handle 11 and in which is formed a hexagonal opening or socket 12 of sufficient size for receiving the correspondingly shaped wrench engaging portion on the shell of a spark plug. Formed on this head

70 at a point opposite to that from which the handle projects, and extending around approximately one-half the diameter of said head, is a flange 13 having an internal rim

75 14 at its upper edge spaced from the body portion of the head to provide a semi-annular recess, for the purpose hereinafter explained, and rotatably mounted on the head is a companion head 16, also provided with a hexagonal opening or socket 17 therein and

80 having a handle 18 projecting from one side thereof, with an outwardly extending annular flange 19 at its lower end a portion of

85 which is adapted to extend into the semi-annular recess of head 10. The handle 18 of the head 16 is attached to or formed integral-

ly with the head at the upper edge thereof, so as to permit a retaining member 20 which holds the heads together to pass under said

90 handle. The retaining member 20 is of the same configuration as the extension and therefore has an inwardly extending rim 21 which overlaps the annular flange 19 of the companion head 16 for holding the heads together so that they may be rotated one on

95 the other. As will be understood this member 20 is of a semi-circular formation to co-

100 operate with the corresponding semi-circular projection on head 10 for holding head 16 in place, and is also provided with small lugs 22

engaging notches 23 in said projecting portion for locking said retaining member against upward movement or away from the head 10, the retaining member and aforesaid projecting portion of the head with which it cooperates forming an annular recess receiving the annular flange on the companion head.

Depending from the retaining member 20 midway of its length is a small lug 24 to engage a recess 25 in the head 10 at the inner end of the handle 11, and extending upward through the handle at one side of said lug is an opening 26 into which is threaded a set screw 27 to bear against the retaining element and hold it securely in place.

The handles 11 and 12 are semi-circular in cross section with flat surfaces 28 adapted to slide one over the other, and in the present instance handle 11 terminates short of handle 18 and is provided in its end with a semi-circular recess 29 cooperating with an inclined shoulder 31 formed by a boss 30 at the projecting outer end of the handle 18, whereby when said handles 11 and 18 are swung towards each other an object, such as the screw-cap or milled nut of a spark plug, when fitted in the semi-circular recess in one handle will be clamped therein against the diagonal shoulder on the other handle for manipulating said cap or nut.

In assembling my improved wrench, the head 16 is placed on the body portion of head 10 and shifted laterally so that flange 19 will seat in the semi-annular recess in the upwardly projecting portion thereof and the hexagonal openings in the two heads align with each other. The retaining member 20 is now secured in place on the head 10 by engaging the lugs 22 in the corresponding sockets in the upwardly projecting portion of said head and manipulating the set-screw 27 to engage lug 24, it being understood that in this operation the set screw is first loosened so that it will not interfere with sliding the retaining member into place, and that handle 18 is swung around opposite handle 11 to be out of the way. When the parts of the wrench are connected the hexagonal openings or sockets in the heads are in alignment and of different sizes corresponding with the wrench engaging portions of the shell and gland nut of a spark plug.

When it is desired to manipulate the parts of a spark-plug in removing the same from the engine handles 11 and 18 of my improved wrench are brought together so that the jaws at the outer end thereof will engage the milled nut or cap which connects the electric conducting wire for loosening the same in disconnecting said wire from the plug. By then placing the aligned heads of my improved wrench over a spark plug so that the larger opening 12 will engage the shell or casing with the gland nut projecting into the smaller

opening 17 and then swinging both levers together in the proper direction the spark plug may be unscrewed and removed from the cylinder block of the engine. After the plug is removed one of the handles may be swung away from the other so as to unthread the gland nut from the shell for separating the parts in examining or cleaning the same.

It is to be noted that my improved wrench is so constructed that the same may be conveniently and efficiently used for disconnecting the electric wire to the plug, for threading and unthreading a plug from the cylinder block, and for separating or assembling the plug itself.

Having thus described my invention, what I claim as new is:

1. A wrench comprising two companion heads each having a socket opening therein, an outwardly extending annular flange on the lower portion of one of said heads, an upwardly projecting semi-circular extension on the other head having a semi-annular recess adapted to receive said annular flange, a semi-circular retaining member connected to the last mentioned head to form a continuation of the semi-annular recess therein and receive the aforesaid annular flange, means at the ends of the aforesaid semi-annular extension and semi-circular retaining member for securing the same together, the head having the extension being provided with a recess opposite said extension, a lug on the semi-circular retaining element projecting into said recess, a set screw threaded into the recess to engage said lug to lock the semi-circular retaining member in connection with the extension on the head, and a handle carried by each of the heads for turning the same.

2. A wrench for the purpose set forth comprising a wrench-head with a handle projecting therefrom, an upwardly projecting semi-circular extension on the wrench-head having a semi-annular recess at the inner side thereof, a companion wrench head having a handle cooperating with the other handle in manipulating the tool, an annular flange on the last mentioned head working in the semi-annular recess in the other head, the first mentioned head having a recess in the upper side thereof opposite the extension thereon, a detachable semi-circular member to form a continuation of said extension and having a depending lug engaging the aforesaid recess, and a set screw threaded into the head carrying the member to engage the latter and hold it in place.

3. A wrench for the purpose set forth comprising a wrench-head with a handle projecting therefrom, an upwardly projecting semi-circular extension on the wrench-head having a semi-annular recess at the inner side thereof and undercut recesses or sockets at its ends, said head having a recess in the upper side thereof opposite the extension, a companion wrench-head having a handle co-

operating with the other handle in manipulating the tool, an annular flange on the last mentioned head working in the semi-annular recess in the other head; together with a detachable member fitting on the first-mentioned head to form a continuation of the semi-circular extension and having lugs engaging the aforesaid sockets and a depending lug intermediate its ends, and a set-screw 5 threaded into the head at the juncture of the handle to engage the depending lug on the detachable member for holding said member 10 in place.

In testimony whereof, I have affixed my
15 signature.

JOHN E. OLSON.
